Specification for Design.

Patented Apr. 22, 1919.

Application filed August 21, 1918. Serial No. 250,886 Term of patent 3½ years.

To all whom it may concern:

Be it known that I, JOHN E. GENN, a citizen of the United States, and a resident of Chicago, in the county of Cook and the State of Illinois, have invented a new, original, and ornamental Design for a Signal-Horn, of which the following is a specification, reference being had to the accompanying drawings, forming a part thereof.

In the drawings:

Figure 1 is a perspective view of a signal horn embodying this design.

Figs. 2 and 3 are respectively front and side elevations of the same.

I claim:

The ornamental design for a signal horn as shown.

In testimony whereof I have hereunto set my hand this 12th day of August, 1918.

J. E. GENN.
